UNITED STATES PATENT OFFICE

JOHN YACOMIS, OF ALBANY, NEW YORK

WINDOW SASH RETAINER

Application filed September 16, 1931. Serial No. 563,173.

This invention relates to an accessory for use in connection with cooperative sliding sashes used in present day window structures, and it has more specific reference to a retainer in the nature of a check applicable to one of the stiles of an upper sash and located for coaction with said sashes to limit the relative sliding movement thereof whereby to restrict the opening to provide for appropriate ventilation and preventing intruders from gaining entrance because of the restricted proportions of said opening.

Window sash checks of this general classification and used for the same purpose are not broadly new. In fact, the art to which the invention relates is sufficiently well developed as to permit definite recollection of the fact that, generically speaking, prior art devices employ projectable and retractable elements adapted for disposition in the path of movement of the correlated sashes to accomplish the purposes previously stated.

A primary purpose of the invention of this application is to generally improve upon known prior arts and marketed checks and retainers by providing one which is structurally different and characterized by such improvements and refinements as serve to produce a novel contribution to the art.

The explicit features and details which serve to characterize and distinguish my improved sash check will become more readily apparent from the following description and drawing.

In the drawing:

Figure 1 is a fragmentary front elevational view showing a pair of window sashes with the device in position on the upper sash.

Figure 2 is an enlarged fragmentary vertical section on the line 2-2 of Figure 1.

Figure 3 is a perspective view of one of the essential parts of the invention.

Figure 4 is a perspective view of the projectable part hereinafter referred to as the spring pressed bolt.

In the drawing the numeral 5 designates the window frame which is conventional, and 6 indicates the upper sliding sash while 7 denotes the lower sash. These sashes are also of ordinary construction. In accord-

ance with the invention one vertical stile of the upper sash as indicated at 8 in Figure 1 is formed with a mortise or socket to accommodate the parts 9 of the attachment. This mortise serves to accommodate the open ended tubular barrel 10 constituting an integral part of the attaching panel or plate 11. This plate may be of any suitable configuration so it is preferably of an elongated shape depicted in Figure 3. It has its upper and lower end apertured at 12 to accommodate a fastening screw 13 as seen in Figure 2. In fact the stile or rail of the sash may be recessed to allow the plate to fit in flush with the surface of the rail. The plate 11 is formed at a point above the horizontal barrel 10 with a vertical slot 14 adapted to accommodate a headed stud 15 on a slidable gravity retaining latch 16. This latch is of any appropriate configuration and formed with a finger button to facilitate operation thereof.

In alignment with the barrel the plate is formed with a circular hole 17 which is here shown as of a diameter less than the barrel so as to provide a substantially annular abutment. To one side this hole or aperture 17 is formed with a notch 18 which constitutes a keyway.

The keyway 18 serves to accommodate a longitudinal rib or key 19 formed on the surface of the cylindrical bolt 20. At its inner end this bolt is provided with a disk like head 21. The bolt is of a diameter to correspond to the aperture 17 and the head 21 of a diameter corresponding to the internal diameter of the tubular barrel 10.

In addition the rib 19 is of a length less than the bolt so as to provide a terminating space at the outer end of the bolt and allowing the adjacent end of the rib to function as a shoulder 22. The numeral 23 designates a coil spring which is housed in the barrel and which bears at its inner end against the socket drilled in the window stile and at its outer end against the head 21. The spring exerts an outward normal thrust against the bolt so that when it is released it is projected to the dotted line position as shown in Figure 2. When thus projected the bolt constitutes a check and is in the path of movement of the

sashes 67 thereby limiting the sliding movement thereof and restricting the top and bottom opening.

As before stated the purpose of this is to provide for ventilation and at the same time provide for safety by preventing intruders from gaining entrance through open windows.

Particularly do I wish to call attention to the one piece construction of the part 9 characterized by a simple attaching plate 11 and horizontally disposed open ended barrel, said barrel being of a diameter greater than the bolt holes 17. Moreover the gravity actuated slideable button or latch 16 is an important feature in that it is easy to lift for releasing the bolt and automatically drop to a position for retaining the bolt in a retracted position. The unusual cooperation of the shortened rib or key 19 in the notch 18 is another desirable feature and the use of said rib as a shoulder for cooperation with the latch is an added feature. Then too the idea of having the barrel 10 open ended adds to the simplicity and economy of manufacture of the part 9 and facilitates assembling and repair, there being no closing cap at the inner end of said barrel. The rib 19 fitting in the notch 18 and the head 21 sliding in the barrel 10 provides a rigid assembly and avoids disalignment and insures appropriate cooperation of the details of a complete unit.

In operation all that is necessary when the bolt is retracted as seen in Figure 2, is to place the finger on the button 16 and to raise it. This releases the bolt and allows it to be projected to the dotted line position depicted in Figure 2 wherein it serves as a suitable retainer for limiting sliding movement of the window sashes.

When the bolt is pushed in to the requisite degree latch 16 drops down by gravity to retaining position to hold the parts in a full line position also shown in Figure 2.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

Having thus described my invention, what I claim as new is:

As a new product of manufacture, a window sash check comprising an attaching plate formed with a vertical slot and below said slot with a bolt hole and a marginal notch associated with the upper part of said bolt hole, said notch being in alignment with the slot, together with an integral open ended cylindrical barrel attached to the inner side of said plate and extending in alignment with

said bolt hole, said barrel having an internal diameter greater than said hole, a bolt of a diameter corresponding to the bolt hole, said bolt being formed at its inner end with a disk like head slideable in the barrel, a spring in said barrel cooperable with said head, said bolt being provided with a longitudinal rib slideable through said notch, a gravity actuated retaining latch comprising a plate having a finger part at its upper end and a stem slideable in said slot, the outer end of said rib terminating short of the adjacent end of the bolt to form a shoulder with which the cooperating end of said latch is engageable.

In testimony whereof I affix my signature. JOHN YACOMIS.
